UNITED STATES PATENT OFFICE.

WILLIAM C. H. CUSHMAN, OF NORTH BENNINGTON, VERMONT, ASSIGNOR TO H. T. CUSHMAN MFG. CO., OF NORTH BENNINGTON, VERMONT, A CORPORATION OF VERMONT.

DESIGN FOR A COMBINED TABLE AND SEWING STAND.

Application filed August 10, 1928. Serial No. 27,776. Term of patent 7 years.

To all whom it may concern:

Be it known that I, WILLIAM C. H. CUSHMAN, a citizen of the United States, and a resident of North Bennington, county of Bennington, State of Vermont, have invented a new, original, and ornamental Design for Combined Table and Sewing Stand, of which the following is a specification, reference being had to the accompanying drawing, forming a part thereof.

In the drawing:

The figure is a perspective view of the article showing my new design.

I claim:

The ornamental design for a combined table and sewing stand substantially as shown.

WILLIAM C. H. CUSHMAN.
